DEVICE FOR CAPPING PUMP TUBING

Filed June 28, 1935

Fig. 1.

UNITED STATES PATENT OFFICE

2,079,922

DEVICE FOR CAPPING PUMP TUBING

Frank M. Owen, Oklahoma City, Okla., assignor
of one-half to American Iron and Machine
Works Company, Oklahoma City, Okla.

Application June 28, 1935, Serial No. 28,867

3 Claims. (CL. 103—202)

This invention relates to a device for capping the pump tubing of an oil or like well and particularly to what is known in oil field parlance as a sucker rod "Christmas tree" through which oil 5 pumped from the well is diverted for flow into a receiving tank.

It is the present practice to assemble a "Christmas tree" from standard pipe fittings connected by suitable nipples; for example, a coupling is 10 usually threaded upon the upper end of the pump tubing to mount a nipple which, in turn, carries a T-fitting having nipples screwed in the vertical and lateral branches thereof to respectively mount a stuffing box and a check equipped flow line 15 leading to the receiving tank. All of these connections are not only expensive but they offer serious leak hazards and make the total height of the tree excessive.

It is, therefore, the principal object of the present invention to provide a simple inexpensive 20 structure incorporating both the stuffing box and the check valve in a single unit.

Other important objects of the invention are to provide a more compact structure, thereby reducing the total height of the assembled tree, and 25 to provide a connection which facilitates assembly thereof in the well pumping apparatus.

In accomplishing these and other objects of the invention as hereinafter pointed out I have provided improved details of structure, the preferred 30 forms of which are illustrated in accompanying drawing wherein:

Fig. 1 is a perspective view of an oil well 35 equipped with a sucker rod "Christmas tree" embodying the features of the present invention.

Fig. 2 is a vertical section through the "Christmas tree" on line 2—2 of Fig. 1.

Fig. 3 is a horizontal section through the tree on 40 line 3—3 of Fig. 2.

Fig. 4 is a vertical section through a modified 45 form of the tree showing a different type of packing gland.

Referring more in detail to the drawing: 50 I designates an oil well including a casing 2 having a casing head 3 through which is extended a string of pump tubing 4 leading to the bottom of the well and which connects with a suitable pump (not shown). The pump is actuated through a string of sucker rods which extend 55 through the pump tubing and connect with a polish rod 5 that is operably connected with a reciprocating mechanism such as a pumping jack 6. Capping the upper end of the tubing 4 is a "Christmas tree" 7 embodying the features of the present invention and wherethrough fluid lifted

by the pump is diverted for flow through a pipe or lead line 8 extending to a suitable receiver (not shown).

The "Christmas tree" 7 includes a body member 9 having a cylindrical portion 10 provided with an axial flow passage 11 in its lower end and an aligning cylindrical packing chamber 12 at its upper end. The lower end of the body member has an annular enlargement 13 providing sufficient thickness of material to accommodate 10 internal threads 14 by which the body member is attached to the threaded end 15 of the pump tubing.

The opposite end of the body member containing the packing chamber is of larger diameter 15 than the lower end to form an internal annular shoulder 16 for seating a washer 17 that has an axial opening 18 to pass the polish rod 5, which extends upwardly through the flow passage 11 and packing chamber 12. Supported by the washer are upper and lower packing rings 19 and 20 that are separated by a spacer 21 including upper and lower flange portions 23 and 24 for respectively engaging the packing sections, and an integral cylindrical web 25 spaced from the polish 25 rod and wall of the packing chamber to form concentric annular lubricant chambers 26 and 27, communicating with each other through suitable openings 29 formed in web, as clearly shown in Fig. 3. Seated against the upper packing section 30 is a washer 30 that is retained in seating relation thereagainst by a packing gland 31.

The packing gland includes a nipple portion 32 slidably engaging within the open end of the packing chamber and bearing upon the washer 35 29 to compress the packing. Formed upon the gland in normally spaced relation with the upper end of the body member are laterally extending ears 33 and 34 which align with similar ears 35 and 36, on the body member as shown in Fig. 1 40 to pass fastening devices such as bolts 37 and 38, for drawing the packing gland into firm engagement with the washer 29, to compress the packing into sealing engagement with the polish rod.

Formed on the side of the cylindrical portion 45 of the body member is a lateral extension 40 having a cylindrical chamber 41 arranged with its axis extending at right angles to the axis of the packing chamber to accommodate a ball 50 check 42 later described. The outer end of the extension is internally threaded as at 43 for attaching the threaded end 44 of the lead line 8. Also formed as an integral part of the body member between the angle of the cylindrical portion 55

10 and the lateral extension 40, is a web 45 having a passageway 46 formed therein and extending upwardly at an angle from the flow passage 11 to communicate through a port 47 with the 5 check chamber 41. Seated over the port is the ball check 42 which prevents back flow of fluid from the lead line 8 when the pump is not operating.

In order to provide a guide for the ball check 10 in movement to and from engagement with its seat the lateral extension is provided with an opening 48, into which is threaded a plug 49 having depending fingers 50 to guidingly engage the ball check and retain it in alignment with its 15 seat. The guide fingers are spaced apart as at 51 to provide flow openings for free outlet of liquid into the lead line 8.

In order to maintain a constant supply of lubricant within the chambers formed by the spacer 20 21, the wall portion 52, which divides the packing chamber from the check chamber, is provided with a port or channel 53 wherethrough fluid trapped within the check chamber may flow into the lubricant chamber; the port preferably being 25 located at the upper portion of the lubricant chamber to maintain it in completely filled condition.

By thus supplying lubricant from the lead line 8 the lubricant chamber is maintained full of 30 lubricant regardless of whether the pump is in operation or not, since there is always a sufficient quantity of liquid trapped within the check chamber and lead line to supply the needs thereof.

The cylindrical body portion of the Christmas 35 tree may be provided with other auxiliary outlet connections as shown at 54, Fig. 2.

The form of the invention shown in Fig. 4 is substantially identical to that above described except for the packing gland 55. In this form of 40 the invention the packing gland includes a cap 56 having an internally threaded flange 57 screwed on to the externally threaded end 58 of the body member. Also engaged by the cap is a depending ring 59 for seating against the upper 45 washer 30. The cap is further provided with ears 60 to which lever arms 61 are pivotally connected and whereby the cap may be readily rotated without the necessity of a wrench or the like.

50 If desired the check valve seat may be provided with a reversible insert seating ring 62 which is retained within the port 63 by the guide fingers 64 on the cage 65.

In assembling a Christmas tree constructed 55 as described the body member is sleeved over the upper end of the polish rod and threaded upon the projecting end of the tubing. The packing sections and spacer are then passed over the polish rod and pushed within the packing chamber 60 after which the packing gland is applied and secured by the drawbolts 37 and 38 to compress the packing in sealed engagement with the polish rod.

The lead line 8 is then connected to the lateral extension of the body member to complete the assembly. Upon operation of the polish rod, oil 5 is lifted within the tubing for flow through the passageway 11, from where it is diverted due to the packing, through the passageway 44, port 47 and check chamber 41 into the lead line 8.

After the pump is operated sufficiently to fill the lead line, the lubricant chamber and packing are kept filled from the check chamber by passage of the liquid through the port 41, so that the packing is kept in pliable condition to effectively seal against the polish rod.

From the foregoing it is apparent that the "Christmas tree" is of compact construction and 15 is readily assembled in connection with the well tubing and flow line without the use of nipples or other fittings as now commonly employed.

What I claim and desire to secure by Letters Patent is:

1. In combination with a well tubing and a pipe line, a capping device for the upper end of the well tubing including a body member having a flow passage and a packing chamber aligning with the flow passage, a packing in said chamber, a lateral extension on the body member having a flow passage communicating with the packing chamber to supply lubricant to said packing, said body member having a flow connection between the flow passage in said body member and the flow passage in the lateral extension, and means on the body member and said extension for respectively connecting the well tubing and pipe line.

2. In combination with a well tubing, a sucker rod reciprocable in the well tubing, and a pipe line, a capping device for the upper end of the well tubing including a body member having a flow passage communicating with the well tubing and the pipe line, means connecting the body member with the well tubing and with the pipe line, a packing in the body member for sealing the sucker rod, check means integrally connected with the body member for controlling reverse flow of fluid from the pipe line, and means for supplying the packing with lubricant from said pipe line.

3. In combination with a well tubing, a sucker rod reciprocable through the well tubing, and a pipe line for conveying well fluid from the tubing, a capping device for the upper end of the well tubing including a body member having a flow passage connected with the tubing and having a packing chamber, means on the body member for connecting the pipe line and having communication with the flow passage, and a channel connecting the flow passage with the packing chamber, a packing in the packing chamber, and a packing gland for compressing the packing about the sucker rod.

FRANK M. OWEN.
